UNITED STATES PATENT OFFICE.

BEREND DETHLEFSEN AND BANDICK FEDDERSEN, OF HAMBURG,
GERMANY.

LOCK FOR CYCLES.

SPECIFICATION forming part of Letters Patent No. 616,775, dated December 27, 1898.

Application filed April 21, 1898. Serial No. 678,391. (No model.)

To all whom it may concern:

Be it known that we, BEREND DETHLEFSEN and BANDICK FEDDERSEN, citizens of Germany, residing at Hamburg, in the Empire of Germany, have invented certain new and useful Improvements in Locks for Cycles, of which the following is a specification.

The lock forming the subject of this invention is intended for locking the handle-bar or the front-fork pillar of cycles in a fixed position to the frame.

The principal characteristics of the lock are that it can be pushed from the back, for instance, through the elbow-bracket for the saddle-post into one of the tubes forming the frame of the cycle and be fixed in the desired position by so arranging the turnable key-pin that it can move in its axial direction under spring action and spring into the key-hole formed in the tube. The key-pin is arranged on one side, preferably so far vertically above the center line of the tube that its under side touches the geometrical center line of the tube, by which arrangement the tube is least weakened. This arrangement of fixing the lock has the advantage that it can very easily and quickly be removed again from the tube to the back for eventual repairs, which are sometimes necessary with such small safety-locks.

Figure 1 of the accompanying drawings is a vertical longitudinal section of the lock; and Fig. 2, a top view of the lock, showing the same in the horizontally-sectioned tube.

The lock shown on the drawings has at each end, back, and front a plate *i*, which fits closely into the tube *w*. The front plate *i* is placed at an incline, so as to fit against the inclined front tube of the frame. Two fixed lock-case plates *y* are attached to the plates *i*, and between the plates *y* the tumblers *e* and bolt *a* are placed, said tumblers being acted upon by springs *k*, as shown, to normally hold them depressed.

g' is the proper key-pin, which can slide longitudinally in the two plates *y*. The front plate *y* has a fixed guide-boss *z*, intended to give additional support to the key-pin *g'*. The key-pin rests with its head *s* against a strong spring *f*, which always has a tendency to push it out through an opening *x* in the

tubular member *w* into the position shown on Fig. 2. The tumblers *e* are hinged upon the fixed pin *d*. A projection or stud *h*, fixed on the bolt, engages into the notches *g* of the tumblers. The back end of the bolt *a* is guided on a peg or stud *a'*, fixed to one of the plates *y* and engaging into a slot *b'* of the bolt. The front end of the bolt is guided in the front plate *i*.

When shutting the lock, the bit of the key inserted into the slot *r* of the key-pin engages into the notch *b* of the bolt *a* and pushes it forward, while at the same time lifting the tumblers, so that the bolt enters into a hole *d'* in the front-fork pillar or the vertical tube of the handle-bar. When the shutting of the lock is completed, the tumblers in the usual way seize over the stud *h*, and thereby lock the bolt.

The bolt *a* is provided with a longitudinal slot or opening *e'*, through which the key-pin *g'* passes, whereby said bolt is free to move longitudinally.

If the lock has to be removed from the tube of the frame for repairs, a stiff rod is screwed into a tapped hole provided in the back plate *i*, and after the pin *g'* has been pushed back against the pressure of spring *f* the whole lock is drawn back by means of the said rod. It is usually sufficient to render the lock virtually immovable in the tube by the friction of the plates *i* or of a circular lock-case connecting these. However, a part not recognizable internally or not removable from the outside may be added in or at the tube, which assures the position of the lock with certainty.

In order to place the lock mechanism in position within the tubular member and to retain the same therein, it is simply necessary to insert the same in the said tubular member from an opening in the rear, as heretofore described, and to then force the same forward until the spring-actuated key-pin *g'* snaps into the side opening *x* in the said tubular member, which will hold the lock mechanism in position and retain the same against a longitudinal and rotary movement until it is desired to remove the lock mechanism, which is accomplished by forcing back the key-pin *g'* until it clears the opening *x*, whereby the

mechanism will be free to be drawn out of the tubular member from the rear, as heretofore explained.

What we claim, and desire to secure by Letters Patent of the United States, is—

1. In combination with a tubular member having a side opening therein, a lock mechanism removably located within said tubular member and having a laterally-movable key-pin, said pin being arranged to enter the opening in the tubular member when the lock mechanism is inserted therein, substantially as and for the purpose specified.

2. In combination with a tubular member having a side opening therein, a lock mechanism removably located within said tubular member and carrying a laterally-movable spring-actuated key-pin, said pin being arranged to enter the opening in the tubular member when the lock mechanism is inserted therein, substantially as described.

3. In a lock for cycles, the combination with a fixed tubular member having a key-hole-opening in one side thereof, of a movable member adapted to be locked to said fixed member, a lock mechanism removably located within said tubular member, a laterally-movable spring-actuated key-pin carried by

the lock mechanism and adapted to snap into the keyhole-opening in the tubular member 30 when the lock mechanism is placed in position therein and a locking-bolt arranged to engage the said movable member, substantially as described.

4. In a lock for cycles, the combination 35 with a fixed tubular member having a key-hole-opening in one side thereof, of a movable member adapted to be locked to said fixed member, a lock mechanism removably located within said tubular member and comprising end plates i , longitudinal plates y , attached to said end plates, tumblers pivoted to said longitudinal plates, a laterally-movable key-pin carried by the said latter-named plates and adapted to enter the keyhole-opening 40 in the said tubular member, a spring normally acting upon one end of said key-pin to force the same outward, and a locking-bolt arranged to engage the said movable member, substantially as described.

BEREND DETHLEFSEN.
